UNITED STATES PATENT OFFICE.

JULIUS B. MELTZ, OF EVERETT, MASSACHUSETTS, ASSIGNOR TO A. L. SMITH IRON WORKS, OF CHELSEA, MASSACHUSETTS, A CORPORATION OF MASSACHUSETTS.

BENDING MACHINE.

Application filed December 28, 1920. Serial No. 433,628.

To all whom it may concern:

Be it known that I, JULIUS B. MELTZ, citizen of the United States of America, and resident of Everett, in the county of Middlesex and State of Massachusetts, have invented new and useful Improvements in Bending Machines, of which the following is a specification.

This invention relates to machines or devices for bending flat bars or strips of sheet material. More particularly the present invention relates to mechanism for use in the making of hangers such as are commonly employed for supporting floor or roof timbers in masonry building construction. Such hangers usually comprise a stirrup of flat bar or strap metal bent to form a bottom member and two spaced, upwardly extending side members which are substantially parallel one to the other at points adjacent said bottom. The side members, substantially midway of their lengths, are twisted in opposite directions whereby to cause their outer ends to lie in planes at right angles to their lower portions, and at the outer ends of said side members the metal is bent to form supporting hooks. The making of hangers of the type just referred to has, so far as is known, been performed heretofore as a hand operation, and as so carried out by hand is slow, laborious, and inaccurate.

The principal object of the present invention is to provide a power driven mechanism capable of operating in an expeditious and accurate manner for producing the bends in the strip or bar of sheet metal necessary for the formation of a hanger, and without requiring the application of heat to the bar. As one mode of attaining the desired object the machine may be provided with a work support having a flat upper surface terminating in a straight edge. Spaced from such surface, may be an anvil block having a face making such an angle with the supporting surface as it is desired that the two parts of the strip of metal assume relatively one to the other and for forcing the strip to conform to the surface of said block, a member rockable about said straight edge of the work support as an axis, may be employed.

For actuating such member, power operated connections may be employed, preferably comprising a one revolution clutch.

As it is desirable that the machine be capable, not only of operating upon sheet or bar material of different thicknesses, but also that it may be able to bend the metal to different angles, the machine may be provided with suitable adjustments for obtaining such desired results. As one method of permitting the machine to operate on metal of different thicknesses, the block against which the metal is bent may be arranged for adjustment toward and from the surface of the work support and if desired for simultaneous adjustment toward and from the edge of the work support. For permitting the machine to bend the material to different angles, the anvil block against which the work is pressed or formed, may be made interchangeable so that blocks having faces at different angles may be substituted one for another. Furthermore the mechanism whereby the movable forming member is actuated may comprise connections such, for example as an adjustable crank-pin whereby the degree of movement of such movable forming member may be varied.

A preferred form of mechanism for carrying into effect the above objects is disclosed in the accompanying drawings, in which Figure 1, is a plan view of the device.

Figure 2 is an end elevation, partly broken away, of the right hand end of the machine as seen in Figure 1;

Figure 3 is a horizontal section on the line A—B of Figure 2;

Figure 4 is a transverse vertical cross section substantially on the line C—D of Figure 1;

Figure 5 is a transverse vertical section on the line E—F of Figure 1;

Figure 6 is a detail elevation of an adjustable crank pin and associated parts which is employed in the driving connections;

Figure 7 is a fragmentary detail elevation of a slotted crank arm shown in Figure 6;

Figure 8 is a side elevation and Figure 9 an end elevation partly in section of a clutch employed in the machine;

Figure 10 is a cross section on the line G—H of Figure 8 illustrating certain details of the clutch mechanism;

Figure 11 is a fragmentary front elevation illustrating the treadle for actuating the clutch, and

Figure 12 is a perspective view illustrating a hanger of the type for use in the making of which, the machine herein disclosed 10 is intended.

This machine is employed in the making of a hanger of the type illustrated in Figure 12. This hanger is formed by bending and twisting a strip or bar of metal of the 15 desired width and thickness. The bottom or supporting portion *a* of the hanger is defined by the upwardly extending parallel legs *b*, *c*. The legs *b*, *c* are oppositely twisted as at *e*, *f* respectively so that their upper 20 portions *g*, *h* lie in planes at right angles to the lower parts thereof. The extremities *k*, *l*, of the legs are again bent at right angles at *m*, *n*, whereby to form backs for engagement with the masonry or supporting girder. 25 The hanger thus constructed serves to support the end of a timber resting on member *a* and positioned by the legs *b*, *c*. The machine of the present invention is intended for making bends at *m*, *n* and *b'*, *c'*.

Referring to the drawings for a more detailed description of the mechanism, 1 is the frame of the machine, comprising a hollow casting having legs 2 at its corners provided with openings 3 by means of which it may 30 be bolted to the floor. Within the frame and projecting from the rear side thereof, are a series of bearing brackets 4, 5, 6 and at the left hand end of the frame is a boss 7. Journaled within suitable openings in 35 the bearing blocks carried by said brackets and in said boss respectively, is a shaft 8 having thereon a pair of driven pulleys 9, 10, of different diameters, such pulleys projecting through suitable openings 11, 12 respectively in the frame. The pulleys 9, 10 are adapted for engagement by a driving belt receiving power from any suitable source. By the provision of pulleys of different diameters, it is possible, by shifting 40 the belt from one to the other, to change the speed of the shaft 8. Fixed upon the left hand portion of the shaft 8, between bracket 4 and boss 7, is a pinion 13.

Projecting from the front wall of the casing and on the interior thereof are brackets 55 14, 15 supporting bearing blocks provided with journal openings which align with a journal opening in a boss 16 on the left hand end wall of the casing. Journaled to turn 60 in the bearings carried by bracket 15 and boss 16 is a shaft 17 having thereon a gear 13^a meshing with gear 13, such shaft having secured adjacent its right hand extremity, the driven element 18 of a clutch device here- 65 inafter described in detail. The bearing

carried by bracket 14 is of substantial length and has journaled therein the driven shaft 19, such shaft having mounted thereon adjacent its left hand extremity the driven clutch element 20.

At 21 is a brake band of any suitable construction which engages the driven shaft or an element thereof, whereby to prevent overthrow of such shaft when the clutch is released.

To the right hand extremity of the shaft 19, as clearly indicated in Figures 6 and 7, is secured a crank arm 22. The crank arm 22 may be fixed in position by means of a pair of keys 23 or in any other suitable 75 manner.

The crank arm 22 is provided with a longitudinally extending slot 24 which extends to a point adjacent the free end of such crank arm. 25 is a crank pin having a fixed 80 collar or shoulder 26, such crank pin extending through the slot in the crank arm and being screw threaded at one extremity as indicated at 27. 28 (see Figure 1) is a yoke having a central opening through 85 which passes the crank pin 25, the yoke being interposed between the collar 26 and arm 22. The opposite ends of the yoke member 28 are bent at right angles, as indicated at 90 29, 30 to embrace the opposite edges of the crank arm 22.

That side of the crank arm opposite that with which the yoke member engages, is roughened or knurled as indicated at 31, such knurling being produced on each side 100 of the slot 24. 32 is a flat plate having a circular opening for the passage of the crank pin 25 and having its opposite ends engageable with the knurled portions of the crank-arm. 33 is a nut which engages the threaded 105 portion of the crank-pin 25 and by means of which the plate 32, yoke 28, and the crank-pin 25 may be firmly locked in an adjusted position on the crank arm 22. Journaled to turn upon the outer end of the 110 crank-pin 25 is a knuckle 34 which is secured thereon by means of a washer 35 and a nut 36 engaging the threaded extremity of the crank-pin.

Secured in a threaded opening in the 115 knuckle 34 is a screw threaded pin 37 formed integral with or fixed to the lower end of a connecting rod 38, such rod extending upwardly through a suitable opening 39 in the upper surface of the machine frame. 120

Mounted upon the upper surface of the machine frame is a bracket device 40 which may be secured to the main frame of the machine by means of bolts 41, or in any other desired manner. In fact such bracket 125 if desired may form an integral part of machine frame. As indicated in Figure 4 the bracket 40 has mounted thereon or integral therewith a member 42 whose upper surface 43 is substantially flat and horizontal and 130

- thus forms a work support or table whereupon material to be bent may be placed. The rear portion of such member 42 is, as indicated in Figure 4, beveled off at 44 whereby 5 to provide a sharp rear edge at 45. The edge 45 is arranged to extend in substantially a straight line transversely of the work table. 46 indicates a bearing bracket secured to the machine frame in any desired 10 manner and in which is journaled to turn a shaft 47. The shaft 47 at its left hand extremity is of reduced diameter, as indicated at 48, and secured upon such reduced portion of the shaft, in fixed relation thereto, is 15 a long lever arm 49. The lever arm 49 adjacent its free extremity is provided with a plurality of spaced openings 50 with either of which may be engaged a pin 51. 52 is a yoke member having spaced arms 53, 54, 20 which lie upon opposite sides of the lever arm 49. The pin 51 passes through suitable openings in the arms 53 and 54 and is held against disengagement therefrom by means of cotter pins 55.
- 25 The yoke member 52 is provided at its lower extremity with an internally screw threaded bore with which engages a screw threaded extension 56 projecting upwardly from the connecting rod 38. The connecting rod, by reason of its screw threaded extensions 37 and 56, is variable in length, thus permitting the proper adjustment of the several parts in setting the machine in 30 position for use.
- 35 60 is a bracket secured upon the upper surface of the machine frame, as by means of bolts 61, such bracket being located just to the left of the work supporting table. The bracket 60 comprises a frame or housing having on its interior surface the upwardly and forwardly extending guide ways 62 and 63. As shown herein, such guide ways are inclined at an angle of substantially 45 degrees to the horizontal, and are 40 substantially parallel. In the preferred form of this device, one side and bottom wall of the guide ways may be integral with the frame, while the opposite side walls thereof are formed by removable plates 64 and 65 respectively, such plates being secured to the frame or housing by screws or bolts.
- 45 The housing is provided with a boss 66 having a journal opening therethrough in 50 which the shaft 47 may turn, such shaft extending to the right of the housing as clearly indicated in Figure 1. At a point opposite the rear edge of the work table, and extending a substantial distance to the right 55 thereof, the shaft 47 is slabbed off to provide substantially flat surfaces 67 and 68 respectively. As the axis of the shaft 47 is arranged substantially coincident with the rear edge 45 of the work table, it is evident that when the shaft 47 is properly po-
- sitioned, the flat surface 67 thereof will 60 form a substantial continuation of the flat upper surface 43 of the work table, lying in the plane thereof. When in this position, the other flat surface 68 of the shaft 65 engages the bevel surface 44 at the rear of the work table, the latter surface thus serving as a stop to limit the turning of the shaft 47 in a clock-wise direction as seen in Figures 2 and 4.

at right angles is employed and the guide ways are arranged as above described, it is clear that when at its lower position of adjustment, the lower right hand angle of the block will coincide with the rear 45 of the work table. It will also be clear that upon movement of the plate 69 upwardly along its guide ways, the surfaces 82 and 83 of the anvil-block will move simultaneously to 10 equal distances from the surface 43 of the work table and from the vertical plane passing through the edge 45, respectively. Thus in accordance with the thickness of the work, the anvil-block may be properly positioned merely by adjusting the screws 72 and 73.

It will be clear that with the parts as shown in Figure 2, a bar or strip of material may be placed upon the work table and 20 pushed beneath the surface 82 until its rear portion overlies the surface 67 of the shaft 47. Upon turning of the crank-arm 22, the lever arm 49 will be actuated and thereby the shaft 47 will be rocked through a partial rotation. Such rocking of the shaft 25 will carry the surface 67 into substantial parallelism with the surface 83 and thus that portion of the work lying to the rear of the edge 43 will be bent upwardly at substantially right angles to the main portion 30 thereof. After the bending of the work, it may be removed from the machine by sliding it to the right from off the work table, the slabbed off portions of the shaft 47 being sufficiently long to permit of such action. If blocks having other angles than a right angle are employed, the position of the crank-pin 25 may be varied whereby to 35 change the effective throw of the crank 22, 40 thereby varying the angle of turning of the shaft 47.

For controlling the operation of the machine the clutch mechanism herein above referred to, is interposed in the driving connections. This clutch as above noted comprises the drive element 18 secured to the drive shaft 17 as by means of the key 90, and the driven clutch element 20 which is 45 slidable upon the shaft 19, being secured against rotation with respect thereto by 50 spline 91. The driving element 18, is provided with the shoulder 92 engageable with the shoulder 93 of the driven element 20 whereby to impart rotation to the latter and 55 therethrough to the shaft 19. In the member 20 is a circumferential groove 94 within which groove engage rollers 95, 96, respectively, carried by a pair of arms 97, 98, said arms being loosely mounted upon a 60 shaft 99 journaled in the machine frame. The arms 97 and 98 are each provided with a boss 100, 101, respectively. Such bosses are arranged for engagement by adjustable stop screws 102, 103, respectively carried by 65 crank arms 104, 105 fast to the shaft 99.

The screws 102, 103 may be secured in adjusted position by means of lock nuts as 106, 107.

110 is a rack bar slidably guided for vertical movement in a member 111 carried by the machine frame, said bar having at its upper end a portion 109 forming a stop dog. Engaging with the rack bar 110 is a toothed sector 112 fast upon the shaft 99. A wedge cam 113 is carried by the clutch element 20, 75 having a surface 114 engageable with the lateral edge of the dog 109. Pivoted at the point 115 on the front side of the machine frame is a treadle lever 116 having a foot 80 engaging part 117. 118 is a spring having one end secured to the treadle lever and having its opposite end fastened to a bracket 119 fixed to the frame. Secured to the left hand end of the treadle lever, as by means of a pivot pin 120 is a link 121 having its 85 other end pivoted at 122 to the right hand extremity of a crank arm 123 fast to the forward end of the shaft 99.

In the operation of the parts just described; it being assumed that the crank 90 arm 22 normally occupies the position shown in Figure 2 and that the clutch elements normally stand in the position shown in Figure 8, the operator having inserted the work in position to be bent, will step upon the treadle 95 117 thereby swinging the shaft 99 and through the action of the sector 112 moving the dog downwardly and out of engagement with the cam surface 114. As the treadle is further depressed the arms 104, 100 105 will be moved upwardly whereby to cause engagement of the screws 102, 103 with the boss 100, 101. The arms 97-98 will thus be moved to slide the member 20 longitudinally of the shaft, thereby pressing the surfaces 92 and 93 into operative engagement.

Upon removing the foot from the treadle, the spring 118 immediately turns the shaft 99 in a clock-wise direction, thereby swinging the arms 104, 105 downwardly and away from the arms 97, 98. At the same time, the sector 112 raises the rack bar 110 so that its upper end 109 lies in the path of the cam surface 114 as the member 20 revolves. 115 Upon engagement of the surface 114 with the member 109, the clutch element 20 is moved positively away from the element 18, thus disconnecting the shafts 17 and 19 and bringing the shaft 19 to rest after a single 120 rotation.

As the crank arm 22 is much shorter than the lever arm 49, such complete rotation of the crank arm 22 serves merely to rock the shaft 47 through the desired arc, such rocking of the shaft 47 taking place during the downward rotation of the crank 22 and the shaft 47 being restored to limited position as the crank 22 completes its rotation. Such restoration of the shaft 47 to initial position 130

releases the material and permits its ready removal from the machine.

While the mechanism above described is regarded as a preferred embodiment of the invention herein disclosed it is clear that various changes and modifications may be made therein and that additions thereto may be made without in any manner departing from the spirit of the present invention.

10 Having thus described the invention in a preferred embodiment of the same together with the mode of operation thereof, what I claim and desire to secure by Letters Patent of the United States is,—

15 1. A machine for bending sheet material comprising a work table having a supporting surface terminating in a substantially straight edge, a work holding block guided for movement in a path oblique to said surface, spring means normally tending to lift said block and a plurality of adjustable stop screws for limiting such upward movement.

2. A machine of the class described comprising a work table having a supporting surface terminating in a substantially straight edge, a block having a work engaging surface, a fixed frame providing guide means engaging said block whereby to guide the same for movement in an oblique path toward and from said edge, means continually tending to move said block away from said edge, and means for adjustably limiting such movement.

3. A machine for bending sheet material comprising a work support terminating in a substantially straight edge, a guide block having work engaging surfaces meeting to form an angle, means for guiding said block for movement along a line intersecting said edge and bisecting said angle, and means continually tending to move said block away from said edge.

4. A machine for bending sheet material comprising a work table having a substantially plane surface, guide means inclined at an acute angle to said surface, a block slidably guided by said guide means for movement toward and from said surface, spring means normally tending to lift said block away from said surface, and adjustable stop means for limiting the movement of said block away from said surface.

5. In combination, a work support having a substantially flat upper surface terminating in a straight edge, a fixed frame providing guides arranged to form an angle of substantially 45° with said surface, a block slidable in said guides toward and from said surface, said block having one surface substantially parallel to the upper surface of the table and an intersecting surface perpendicular thereto, a rod secured to said block and passing through said frame, a spring engaging a stop carried by said rod whereby normally to lift said block, a stop

screw adjustably mounted in the frame for engaging said block to limit its upward movement, and a bending element mounted for swinging movement on a shaft having its axis substantially coincident with the straight edge of said support for disposing the work against the perpendicular surface of said block.

6. A machine for bending metal comprising a holder comprising an interchangeable work engaging block, a movable bending element cooperable with said block for forming the metal between the same and said block, and means for moving said bending element, said means comprising adjustable connections whereby the amount of movement of said element may be varied.

7. In combination, in a machine of the class described, a rockable bending element and means for rocking said element comprising a power shaft, a slotted crank arm thereon, a crank pin adjustable along the slot of said arm, a yoke member provided with an opening for the passage of said crank pin and with members engageable with the lateral edges of said crank arm, and means for fixing said pin and yoke member in adjusted position.

8. In a machine for bending sheet material, a bending element, a power shaft and connections between said shaft and element for actuating the latter, said connections comprising a slotted crank arm fast to said shaft, a yoke member provided with a central opening and having ears engaging the edges of said crank arm, a shouldered crank pin passing through said opening and the slot in the crank arm, a plate having a central opening for the passage of said pin and engaging said arm upon opposite sides of its slot, and a nut engageable with screw threads on said pin for clamping the several parts in adjusted position.

9. In a metal bending machine, a bending element carried by a shaft journaled for rocking movement, a drive shaft, and adjustable connections between said shafts comprising a slotted crank arm fast on the drive shaft, one face of said arm being knurled at opposite sides of said slot, a crank pin slidable in said slot, a plate having an opening for said pin and engageable at its opposite ends with said knurled portions of the crank arm, and means for clamping said plate in adjusted position.

10. A bending machine comprising a rockable bending element, a lever arm for moving the same, a drive shaft, means for turning said shaft including a one revolution clutch, a crank arm fast to said drive shaft, said crank arm being of lesser length than said lever arm, and a connecting rod for transmitting movement from the former to the latter.

11. A machine for bending sheet material

comprising a work support having a substantially straight edge, a rock shaft journaled to turn about an axis substantially coincident with said edge, said shaft having a slabbed off portion normally forming a continuation of said work support, a drive shaft, a power shaft, a one revolution clutch interposed between said last named shafts,

a foot treadle for controlling said clutch, and connections between said drive shaft 10 and said rock shaft whereby a complete rotation of the drive shaft serves to turn said rock shaft through a predetermined angle.

Signed by me at Boston, Massachusetts, this 24th day of December 1920.

JULIUS B. MELTZ.
